UNITED STATES PATENT OFFICE.

ERIC W. PALMQUIST, OF EAST ST. LOUIS, ILLINOIS, ASSIGNOR TO LEIGHTON & HOWARD STEEL COMPANY, OF ST. LOUIS, MISSOURI, A CORPORATION.

BOLSTER.

SPECIFICATION forming part of Letters Patent No. 702,818, dated June 17, 1902.

Application filed March 8, 1902. Serial No. 97,317. (No model.)

To all whom it may concern:

Be it known that I, ERIC W. PALMQUIST, a citizen of the United States, residing in East St. Louis, in the county of St. Clair and State 5 of Illinois, have invented certain new and useful Improvements in Bolsters, of which the following is a full, clear, and exact description, reference being had to the accompanying drawings, forming part of this specification.

My invention relates to a bolster so formed that while provision is made for the use of the king-bolt, yet it is done in such a manner as not to materially weaken the bolster at its 15 central or middle portion.

The invention consists in features of novelty hereinafter fully described, and pointed out in the claims.

Figure I is a top or plan view of my improved bolster, part in horizontal section. Fig. II is a side view, part in vertical section. Fig. III is a vertical transverse section taken on line III III, Fig. II.

1 represents the bolster, which in general 25 form or shape may be of any approved style. I have shown it as composed of an upper flange or chord 2, a lower flange or chord 3, and a connecting-web 4.

5 is the king-bolt opening, located at the 30 base of the center bearing 6. This opening is formed in a post 7, that is cast integral with the body of the bolster and which is strengthened by integral wings 8. About the middle of the web portion of the bolster there is

formed an integral boss or enlargement 9, 35 through which passes a horizontal aperture 10. As will be observed from the drawings, the king-bolt opening only extends through the upper portion of the bolster, the lower portion of the bolster being left imperforate, 40 so that its strength is not impaired. The horizontal opening 10 provides means of access to the lower end of the king-bolt, so that a key can, if desired, be passed through the bolt, and the horizontal aperture also affords 45 means for prying the king-bolt out when necessary for it to be removed.

I claim as my invention—

1. A bolster consisting of an upper and lower chord, and a connecting-web, said upper 50 chord and the upper portion of the connecting-web being formed with a king-bolt opening, and said web having a horizontal opening at the base of the king-bolt opening, substantially as set forth. 55

2. A bolster having an upper and lower chord, a connecting-web, a post formed integral with the upper chord and the upper part of said web, and which is provided with a king-bolt opening and a horizontal boss 60 formed integral with said web and through which an aperture is formed, substantially as described.

ERIC W. PALMQUIST.

In presence of—
E. S. KNIGHT,
N. V. ALEXANDER.
